UNITED STATES PATENT OFFICE.

ALFRED GEORGE FOX, OF NEW CROSS, ENGLAND.

CHAIN GRATE.

1,386,857.

Specification of Letters Patent. Patented Aug. 9, 1921.

Application filed April 26, 1917. Serial No. 164,706.

To all whom it may concern:

Be it known that I, ALFRED GEORGE Fox, a subject of the King of Great Britain, residing at 87 Erlanger road, New Cross, in 5 the county of Kent, England, have invented certain new and useful Improvements in Chain Grates, of which the following is a specification.

This invention relates to automatic stokers 10 of the type in which burning fuel is fed from the front to the rear of the furnace by movement of the grate, for example by a power driven continuous chain grate. In conjunction with such grates it is usual to 15 employ a number of dumper bars, or ash plates, pivoted about a fixed beam or bearer bar and extending across the rear end of the grate which serve to divert the clinker and ash into a storage hopper or ash pit from 20 which it may be withdrawn at intervals through suitable dampers; at the same time the dumper bars preserve an effective air seal to the furnace.

It is essential for efficient utilization of 25 the fuel that no unburned fuel passes over to the hopper and also that the burning fuel should properly cover the whole of the grate up to the dumper bars in order to prevent air leakage through the grate, and consequent lowering of the efficiency of 30 the boiler. It is equally or even more important that the ash and clinker shall not effect a lodgment, beyond a limited extent, and accumulate at the dumper bars, but shall continue freely to pass over them and discharge 35 into the storage hopper.

This invention consists in providing dumper bars mounted indirectly through pivoted supporting bodies upon bearer bars 40 which are adjustable along a path such that the ash receiving face of the dumper bar may be moved between position substantially above and below the upper grate level and will form a practically air-tight seal 45 therewith in all positions, while a second practically air-tight seal is formed by the aforesaid supporting bodies engaging with a stationary member such as a fixed plate. The invention further consists in improvements 50 in the construction and arrangement of the various parts so that the renewal of parts can be readily effected and the possibility of jamming during working or of the dumper bars being pushed back is avoided.

55 The adjustment of the dumper bars may

be hand controlled and discontinuous, or automatic and continuous, according to the class of fuel being burned. I have found that by the use of such adjustable bars more uniformly efficient results may be obtained from a boiler with different classes of fuel than has been possible hitherto.

In carrying this invention into effect I pivotally support the lower ends of the dumper bars (which may be separate or in 60 sections) on pivoted members mounted on a movable bearer bar which extends across the furnace so that the upper ends of the dumper bars make a sliding practically air-tight joint with the rear end of the grate 65 while the pivoted members which are the direct support of the dumper bars make a similar joint with the side or bottom of the ash-pit in which the ash and clinker is collected. The bearer bar may be moved up 70 and down for adjustment of the position of the noses of the dumper bars by rack and pinion mechanism or by eccentrics on a shaft extending through the furnace wall beneath 75 the grate or by other suitable well-known 80 mechanism for enabling the adjustment to be made from the outside of the boiler furnace.

The movable bearer bar carrying the dumper bars may be connected to one arm of 85 a pivoted lever or levers under the grate or on the rear axle of the grate, the other arm of this lever being fitted with a counter-balance weight so as to enable the bar to be 90 easily moved by the actuating mechanism.

The invention will be better understood by reference to the accompanying drawings in which Figures 1 and 2 represent elevation and plan respectively of portions of a grate constructed according to my invention.

In the drawings, *a* represents the rear end 95 of a chain grate, the rear axle of which is generally made adjustable longitudinally of the grate to accommodate for changes in 100 the length of the grate due to expansion, wear of the link holes and link rods or other causes. These links generally form a series of flats or chords as they pass over the guide wheels at the ends of the grate. The 105 dumper bars *b* bear against the rear end of the grate and are pivotally supported indirectly on an adjustable bearer bar *c* through a plate or body portion *d* which may be 110 continuous across the width of the grate.

but which I prefer to make in a number of sections. The pivotal mounting of the dumper bars is such that they have only a limited movement away from the grate so as to prevent them from being thrown off their supports or remaining fixed in a raised position should a large piece of clinker pass underneath the nose of the bar. This is accomplished by providing the bearer bar or supporting member with an upwardly projecting portion *s* which is substantially V-shaped in cross section and forming a corresponding V-shaped groove bearing portion *t* in the lower portion of the dumper bar. The sides of the V-shaped groove embrace a slightly larger angle than sides of the bearer bar so that the dumper bar may have a certain movement. As shown both the bearer bar and the groove in the dumper bar may have flattened engaging portions.

In some cases a fixed stop may be provided to prevent the dumper bars from being moved too far from the grate. The plate *d*, whether made continuous or of a number of sections, is also pivotally suspended from the bearer bar *c* and the center of support of bar *b* is so arranged that the lower edge of the plate *d* is held by gravity, no matter what the position of the bar *c* is, against a plate *e* secured to or forming the bottom or a side of the ash pit so as to make a continuous and practically air-tight seal therewith. The door *g* through which the clinker and ash are withdrawn may bear against the lower side of the plate *e*, as shown in the drawing. The dumper bars *b* make a second substantially air-tight seal with the end of the grate. The bearer bar *c* is adjustable along the arcuate path *x-y* which is concentric with the rear axle of the grate so as to arrange that the noses of the dumper bars bear against the portion of the grate most suitable for the type of fuel being consumed. The bar *e* is constrained to the path *x-y* by a slotted member *q* at each end of the bar.

The adjusting mechanism forms no part of the present invention but may be of any well-known or suitable type and may be power driven or operated by hand. The mechanism shown is merely an example.

The upper or working ends of the dumper bars *b* are preferably made renewable as has hitherto been proposed by being dovetailed on to the major portion, as shown, and I may also form the upper surface with slots or perforations *b'* for the admission of air and to allow of the better combustion of fuel and cooling of clinker lying against the bar as has also been proposed.

This construction and mounting of dumper bars and pivoted supporting body above described and illustrated in Figs. 1 and 2 I have found in practice to be a very satisfactory form of the invention, afford-

ing as it does the following, among other, advantages:

(1) Absence of jamming; considerable elasticity, adjustment of the rear shaft and stretching of the grate, etc., or other relative movement between grate and ash pit wall, being permissible by reason of the interplay of dumper and supporting bars.

(2) Wide angular rotation of the ash receiving face between "banking" and "clearing" positions, rendering the system adaptable to fuels having widely different burning characteristics.

(3) Quick and ready renewal of burned or otherwise defective parts of the dumper or supporting bars owing to their not being bolted or threaded on a shaft.

(4) Pushing or rocking back of the dumper bars, (a common trouble) avoided; limited clearing movement only being allowed.

(5) Complete and constant air sealing in all positions.

(6) when the noses of the dumper bars shorten by burning each individual bar adjusts itself automatically to the grate so that the seal is kept continuous.

What I claim as new and desire to secure by Letters Patent of the United States, is:—

1. In combination with a furnace having a traveling grate, dumper bars forming an air seal with the grate, supporting means for said bars comprising a shaft and bar-supporting members between said shaft and said bars, said supporting means being adapted to be adjusted to position the dumper bars either above or below the grate surface, a fixed member, and interplay devices adapted to form an air seal with the fixed member.

2. The combination with a furnace having a traveling grate, of dumper bars forming an air seal with the grate, supporting means for said bars comprising a shaft adjustable parallel to itself and bar-supporting members between said adjustable shaft and said bars, said bar-supporting means being adapted to be adjusted to position the dumper bars either above or below the grate surface, a fixed member, and air sealing devices adapted to maintain a seal with the fixed member.

3. In combination with a furnace having a traveling grate, a fixed member, a shaft adjustable parallel to itself, bar-supporting members on the shaft, interplay extensions on the supporting members forming an air seal with the fixed member, dumper bars pivotally mounted on the bar-supporting members and adapted to maintain an air seal with the grate, the adjustment of the shaft being adapted to position the dumper bars above or below the grate surface.

4. The combination with a furnace having a traveling grate, of a fixed member, a shaft,

- bar-supporting members removably supported on the shaft and having integral extensions adapted to form an air seal with the fixed member, dumper bars removably supported on the bar supporting members, and forming an air seal with the grate, the shaft being adjustable parallel to itself to position the dumper bars above or below the grate surface.
- 10 5. The combination with a furnace having a traveling grate, of a fixed member, a shaft adjustable parallel to itself, members seated on the shaft, each of said members comprising a shoulder and a relatively long extension, said member being so proportioned

that the extensions are positioned by gravity in contact with the fixed member in all positions of the shaft, dumper bars seated on the shoulder of each member and being so proportioned that one edge thereof is positioned by gravity against the grate surface in all positions of the shaft, the shaft being adapted to position the dumper bar above or below the surface of the grate. 20

In witness whereof, I have hereunto set 25
my hand this 11th day of April, 1917.

ALFRED GEORGE FOX.
